(57) **CLAIM**

I claim the ornamental design for a set of resistance bands with handles, as shown and described.

DESCRIPTION

FIG. 1 is a front view of the set of resistance bands with handles showing my new design;

FIG. 2 is a perspective view of set of resistance bands with handles assembly with handles attached;

FIG. 3 is a perspective view of a set of resistance bands with handles in the form of a ring, where both edges of the set of resistance bands with handles are connected to one another;

FIG. 4 is a perspective view of set of resistance bands with handles, i.e., of two connected bands with handles; and,

FIG. 5 is a perspective view of set of resistance bands with handles assembly with handles view thereof.

In the drawings, the evenly-spaced broken lines depicts stitching which forms part of the claim; the dash-dot-dash lines represent environment and form no part thereof.
